US00D355430S

United States Patent [19]

Hofmann-Igl

[11] Patent Number: Des. 355,430

[45] Date of Patent: ** Feb. 14, 1995

[54] STEREOMICROSCOPE

[75] Inventor: Ernest Hofmann-Igl, Davos-Platz, Switzerland

[73] Assignee: Leica AG, Heerbrugg, Switzerland

[**] Term: 14 Years

[21] Appl. No.: 16,732

[22] Filed: Dec. 22, 1993

[30] Foreign Application Priority Data

Jul. 12, 1993 [DE] Germany M9305537.4

[52] U.S. Cl. D16/131

[58] Field of Search D16/131; 359/385, 376, 359/390, 801, 377, 378

[57] CLAIM

The ornamental design for a stereomicroscope, as shown and described.

DESCRIPTION

FIG. 1 is a perspective view of a stereomicroscope showing my new design;

FIG. 2 is a right side elevational view thereof, the left side being a mirror image thereof and is thus not shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a second embodiment of a stereomicroscope showing my new design;

FIG. 8 is a right side elevational view thereof, the left side being a mirror image thereof and is thus not shown;

FIG. 9 is a front elevational view thereof;

FIG. 10 is a rear elevational view thereof;

FIG. 11 is a top plan view thereof;

FIG. 12 is a bottom plan view thereof;

FIG. 13 is a third embodiment of a stereomicroscope showing my new design;

FIG. 14 is a right side elevational view thereof, the left side being a mirror image thereof and is thus not shown;

FIG. 15 is a front elevational view thereof;

FIG. 16 is a rear elevational view thereof;

FIG. 17 is a top plan view thereof; and,

FIG. 18 is a bottom plan view thereof.
